UNITED STATES PATENT OFFICE

PAUL H. GEIGER, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

ELECTRICAL APPARATUS

Application filed July 10, 1928. Serial No. 291,664.

My invention relates to electrical apparatus, and particularly to apparatus of the type comprising a load supplied with energy from a source of pulsating current.

5 One object of my invention is the provision, in apparatus of the type described, of means for smoothing out the pulsations in the current supplied to the load.

The present case is a continuation of my 10 co-pending application, Serial No. 61,211, filed October 8, 1925, for Electrical apparatus, in so far as the matter common to the two cases is concerned.

I will describe several forms of apparatus 15 embodying my invention, and will then point out the novel features thereof in claims.

In the accompanying drawing, Fig. 1 is a diagrammatic view illustrating one form of electrical apparatus embodying my invention. Figs. 2, 3 and 4 are views showing modified forms of the apparatus illustrated in Fig. 1 and also embodying my invention. Fig. 5 is a view showing a modified form of the apparatus illustrated in Fig. 4 and also 25 embodying my invention.

Similar reference characters refer to similar parts in each of the several views.

Referring first to Fig. 1, the apparatus comprises a source of pulsating current which 30 as here shown is a rectifier R supplied with energy from the secondary 2 of a transformer T. The primary 1 of this transformer is supplied with alternating current from a source not shown in the drawing.

35 The rectifier R supplies pulsating current to a load which may be any current consuming device and is here illustrated as the filament 6 of an electron tube A similar to those used in radio receiving circuits and the like.

40 The filament 6 of this tube is connected with the output terminals *a* and *b* of the rectifier R. In order to reduce or smooth out the pulsations in the current flowing through the load, which pulsations, in the case of an electron tube, would cause undesirable pulsations in the plate current of the tube, I connect the secondary of a transformer K in series with 45 the filament 6. The primary 4 of this transformer is connected directly across the ter-

minals *a* and *b* of the rectifier in series with a variable resistance 5.

The pulsations in the current flowing through the secondary 3 of the transformer K induce, in the secondary 3, an electro-motive force which tends to oppose these pulsations. The pulsating current in primary 4 of transformer K also induces in secondary 3 an electromotive force which tends to oppose the pulsations in the load circuit. As a result of these two induced electromotive forces, the pulsations in the current flowing through the filament 6 are smoothed out and substantially eliminated. By means of the resistance 5 the apparatus may be adjusted to give the maximum smoothing effect.

One advantage of the apparatus embodying my invention over apparatus already known is that a given smoothing effect may be obtained with comparatively small smoothing reactors arranged in the form of a transformer K. The same smoothing effect cannot be accomplished with windings of similar size simply inserted in series with the load.

In the form of the apparatus shown in Fig. 2 the various parts are arranged in a manner similar to the arrangement shown in Fig. 1 with the exception that an auxiliary reactor 80 X is connected in series with the filament 6 of tube A. The purpose of this reactor is to further smooth out the pulsations in the current flowing through the filament.

In Fig. 3 the reactor X is connected in series with the filament 6 and also with the primary 4 of transformer K. The operation of the apparatus is the same as in Figs. 1 and 2.

Referring now to Fig. 4, the load which is supplied with current from the rectifier R is divided into two portions, one comprising the filament 9 of an electron tube C, and the other portion comprising the filaments 8 of a plurality of electron tubes such as B¹ and B². The tube C may be the detector, and tubes B¹ and B² may be the audio-frequency amplifiers, of a radio receiving system.

The transformer K¹ is an auto transformer comprising a winding divided into a primary 100

4 and a secondary 3 by an adjustable tap t . The amplifiers B^1 and B^2 have their filaments 8 supplied with pulsating current from terminals a and b of the rectifier R through the secondary 3 of transformer K^1 and the smoothing reactor X in series. The filament 9 of the detector tube C is connected with terminals a and b of rectifier R through primary 4 of transformer K^1 , an adjustable 10 resistance 5, and the smoothing reactor X . The pulsating current through secondary 3 induces an electromotive force which tends to oppose these pulsations, and the pulsating current in primary 4 also induces an electro- 15 motive force in secondary 3 which tends to oppose the pulsations in the circuit through the filaments 8. The resistance 5 and the tap t may be adjusted to obtain the maximum smoothing effect.

20 In radio receiving apparatus, however, the variations in the filament current of the detector tube causes variations in the plate current of the detector tube which in turn are applied to the grid circuit of the amplifier tubes; and so are amplified and affect the plate current of the amplifiers. The parts of the apparatus shown in Fig. 4 are so arranged and proportioned that the pulsations caused in the amplifier plate current by the pulsations in the filament 9 of the detector tube C oppose the pulsations caused in the plate current of the amplifier by pulsations in the filaments 8 of the amplifiers themselves. The effect, then, of the pulsations in the detector 30 filament current neutralizes the effect of the pulsations in the amplifier filament current, in so far as their action upon the amplifier plate current, is concerned. In actual operation the adjustable tap t of transformer K^1 40 and the resistance 5 are adjusted to give the maximum smoothing effect upon the amplifier plate current. These adjustments may then be made permanent and all variations in the magnitudes of the currents supplied to the 45 electron tube filaments may be made by means of an adjustable resistance 10 interposed between the secondary 2 of transformer T and the input terminals of the rectifier R .

I have discovered that with the apparatus 50 illustrated in Fig. 4 the filaments of the tubes of a radio receiving system utilizing three stages of audio-frequency amplification may all be energized from a sixty-cycle alternating current source without perceptible pulsations in the output of the third stage.

In the modified form of apparatus shown 55 in Fig. 5, the circuits are similar to those shown in Fig. 4 except that a resistor 21 is connected across the reactor X and the rectifier R to further improve the smoothing action of the reactor. In the form here shown, the reactor X comprises a core 11 of magnetizable material having a middle leg 13 provided with a winding 12. Current in the 60 winding 12 creates flux which traverses the

two legs 14 and 14^a of the core in parallel.

The transformer K^2 comprises a core having three magnetizable legs 16, 17 and 18 connected in parallel. Winding 4 is located on leg 17 and is connected in series with the filament 9 of the detector tube C . Leg 18 carries winding 3 connected in series with the filaments 9 of the amplifier tubes B^1 and B^2 . The leg 18 includes an air gap 19 which may be varied by moving member 20 in a horizontal direction as shown in the drawing. The parts are arranged, as in Fig. 4, in such manner that the pulsations in the detector tube filament circuit oppose the effects of pulsations in the amplifier tube filament circuits, in so far as their effects upon the amplifier plate circuits is concerned.

It will be seen that the pulsating flux created by current in winding 4 divides between legs 16 and 18. By properly adjusting the member 20, the air gap 19 may be brought to such value that the proportion of this flux linking winding 3 substantially neutralizes the effect of these pulsations in the output circuit of the last stage amplifier.

Although I have herein shown and described only a few forms of electrical apparatus embodying my invention, it is understood that various changes and modifications may be made therein within the scope of the appended claims without departing from the spirit and scope of my invention.

Having thus described my invention, what I claim is:

1. The combination with radio receiving apparatus comprising a detector tube and an amplifier tube and a source of pulsating current, of a first winding and a second winding in inductive relation, a circuit for said detector tube including said source and said first winding, and a circuit for said amplifier tube including said source and said second winding.

2. The combination with radio receiving apparatus comprising a detector tube and an amplifier tube and a source of pulsating current, of a first winding and a second winding in inductive relation, a circuit for the filament of said detector tube including said source and said first winding, and a circuit for the filament of said amplifier tube including said source and said second winding.

3. The combination with radio receiving apparatus comprising two electron tubes and a source of pulsating current connected with the filaments of said tubes in parallel, of two windings in inductive relation one interposed in series with each said filament.

4. In combination, a source of pulsating current, two loads connected in parallel with said source, and means for reducing the pulsations in the current through at least one of said loads and comprising two windings in inductive relation one interposed between each said load and said source.

5. The combination with radio receiving apparatus comprising a detector tube and an amplifier tube, of a source of pulsating current connected with the filament of said amplifier tube, and means for supplying from said source to the filament of said detector tube a pulsating current differing in phase from the current in said amplifier tube.

6. The combination with radio receiving apparatus comprising a detector tube and an amplifier tube and a source of pulsating current, of a transformer having three legs connected in parallel, two windings located on two of said legs respectively, a circuit for the filament of the detector tube including said source and one of said windings, and a circuit for the filament of the amplifier tube including said source and the other winding.

20 7. The combination with radio receiving apparatus comprising a detector tube and an amplifier tube and a source of pulsating current, of a transformer having three legs connected in parallel, two windings located on two of said legs, respectively, means for varying the coupling between said windings, a circuit for the filament of the detector tube including said source and one of said windings, and a circuit for the filament of the amplifier tube including said source and the other winding.

8. In combination with radio receiving apparatus comprising a detector tube and an amplifier tube and a source of pulsating current, of a transformer having three legs connected in parallel, two windings located on two of said legs respectively, means for varying the reluctance of one of said two legs, a circuit for the filament of the detector tube including said source and one of said windings, and a circuit for the filament of the amplifier tube including said source and the other winding.

9. The combination with radio receiving apparatus comprising a detector tube and an amplifier tube and a source of pulsating current, of a transformer having three legs connected in parallel, two windings located on two of said legs respectively, an air gap in one of said legs, a circuit for the filament of the detector tube including said source and one of said windings, and a circuit for the filament of the amplifier tube including said source and the other winding.

55 10. The combination with radio receiving apparatus comprising an electron tube, of a transformer having three legs connected in parallel, two windings located on two of said legs respectively, means for varying the reluctance of one of said two legs; a circuit including one of said windings, said source and the filament of said electron tube; and means for connecting the remaining winding with said source.

65 11. The combination with radio receiving

apparatus comprising an electron tube, of a transformer having three legs connected in parallel, two windings located on two of said legs respectively, means for varying the reluctance of one of said two legs; a reactor; a circuit including said source, said reactor, one of said windings, and the filament of said electron tube; a resistor connected across said reactor and said source, and a second circuit including said source and the remaining winding.

In testimony whereof I affix my signature.
